US0D1106125S

(12) **United States Design Patent** (10) **Patent No.:** **US D1,106,125 S**
(45) **Date of Patent:** **** Dec. 16, 2025**

(54) **RFID TAG**

(71) Applicant: **Murata Manufacturing Co., Ltd.**,
Nagaokakyo (JP)

(72) Inventors: **Noboru Kato**, Nagaokakyo (JP);
Mikiko Saito, Nagaokakyo (JP)

(73) Assignee: **Murata Manufacturing Co., Ltd.**,
Nagaokakyo (JP)

(**) Term: **15 Years**

(21) Appl. No.: **29/830,621**

(22) Filed: **Mar. 14, 2022**

Related U.S. Application Data

(62) Division of application No. 29/726,476, filed on Mar.
3, 2020, now Pat. No. Des. 949,834.

(57) **CLAIM**

The ornamental design for an RFID tag, as shown and
described.

DESCRIPTION

FIG. 1 is a front, bottom, and right side perspective view of
a first embodiment of an RFID tag showing our new design;
FIG. 2 is a rear, top, and left side perspective view thereof;
FIG. 3 is a front view thereof;
FIG. 4 is a rear view thereof;
FIG. 5 is a top view thereof;
FIG. 6 is a bottom view thereof;
FIG. 7 is a right side view thereof;
FIG. 8 is a left side view thereof;
FIG. 9 is a front, bottom, and right side perspective view of
a second embodiment of an RFID tag showing our new
design;

FIG. 10 is a rear, top, and left side perspective view thereof;
FIG. 11 is a front view thereof;
FIG. 12 is a rear view thereof;
FIG. 13 is a top view thereof;
FIG. 14 is a bottom view thereof;
FIG. 15 is a right side view thereof; and,
FIG. 16 is a left side view thereof.

The broken lines shown in the drawings illustrate portions of
the RFID tag that form no part of the claimed design. The
dash-dot lines illustrate a boundary of the RFID tag that
forms no part of the claimed design.

(Continued)

The oblique surface shading in FIGS. 1, 3 9 and 11 illustrates transparent portions of the RFID tag that form part of the claimed design.

1 Claim, 16 Drawing Sheets
